UNITED STATES PATENT OFFICE.

ERNST MALKE, OF CONNEWITZ, NEAR LEIPSIC, SAXONY, GERMANY.

FEED MECHANISM FOR MUSIC-BOXES.

SPECIFICATION forming part of Letters Patent No. 427,097, dated May 6, 1890.

Application filed August 29, 1889. Serial No. 322,345. (No model.)

To all whom it may concern:

Be it known that I, ERNST MALKE, of Connewitz, near Leipsic, in the Kingdom of Saxony, Germany, have invented an Improved 5 Feed Mechanism for Music-Boxes, of which the following is a specification.

This invention relates to a feed mechanism for music-boxes which is more particularly designed to feed very thin perforated paper 10 over the sound-producing devices. Such paper would be apt to become easily crumpled when fed by friction-rollers. I have devised a feed mechanism which positively draws the paper forward through the instrument.

15 The invention, briefly stated, consists in a pair of endless belts connected at one point by a cross-bar, which is adapted to hold the forward edge of the paper. Thus the motion of the belts feeds the paper over the reeds or 20 valves that produce the sound.

In the accompanying drawings, Figure 1 is a vertical longitudinal section of a music-box having a comb of sounding-teeth and provided with my improved feed mechanism. Fig. 2 is 25 a vertical cross-section on line xx , Fig. 1. Fig. 3 is a vertical cross-section on line zz , Fig. 1; Fig. 4, a face view of the cross-piece Q; Fig. 5, a section on line yy , Fig. 4, showing the catch closed; Fig. 6, a similar section with the 30 catch open. Fig. 7 is a vertical longitudinal section of a valve music-box provided with my invention, and showing the valves closed. Fig. 8 is a similar section with the valves open.

The letter A represents a music-box of suitable construction and having either comb-teeth A', as in Fig. 1, reeds with valves A², as in Figs. 7 and 8, or other equivalent music-producing devices which are put into action by a perforated sheet of paper in the well-known manner.

A³ represents the crank-shaft of the music-box, to which power is applied and upon which are rigidly mounted two disks S S, one near each end.

B B are a pair of endless belts or bands 45 passing over the disks S S and over a series of disks L L, hung loosely upon their shafts A⁴. Between the disks S S and between the disks L L rollers M are loosely hung upon their shafts. The bands B B are connected at any suitable 50 point by a cross-bar Q, such cross-bar being provided at its end with perforations p, adapted to engage buttons r on belts B. Thus the cross-bar can be readily attached or removed. The cross-bar Q is adapted to firmly engage 55 one edge of the perforated music-sheet N. To this effect it is provided with a catch of any suitable construction.

In use the sheet N is secured to the cross-piece Q, the latter is slipped over buttons r, 60 and the crank-shaft A³ is turned. The sheet N will be drawn between bands B over the several rollers M by a positive feed, and will thus at all times be kept perfectly taut.

To remove the sheet N, it is only necessary 65 to detach it from the cross-piece Q, when it may be freely drawn out of the music-box.

What I claim is—

1. The combination of a music-box with a pair of endless belts B, and with a cross-piece 70 Q, connecting the belts and provided with a catch for engaging the music-sheet, substantially as specified.

2. The combination of music-box A with a series of shafts carrying disks and rollers, and 75 with a pair of endless belts B, having buttons r and passing over the disks, and with a cross-piece Q, having a catch and adapted to be engaged by said buttons, substantially as specified.

In testimony whereof I have signed my name to this specification in the presence of two subscribing witnesses.

ERNST MALKE.
